PROPELLER BLADE TESTING APPARATUS

Robert C. Treseder, Dayton, Ohio, assignor to General Motors Corporation, Detroit, Mich., a corporation of Delaware

Application August 2, 1952, Serial No. 302,321

7 Claims. (Cl. 73—147)

The present invention relates to testing apparatus and more particularly to apparatus for ascertaining the structural characteristics of propeller blades.

Existing apparatus for determining the structural characteristics of propeller blades is inadequate. Modern practice dictates the necessity for providing test apparatus to obtain the requisite data on blade strength by closely approximating or duplicating flight propeller loadings in the laboratory. The present invention provides means for inducing flatwise vibratory stresses in propeller blades by torsional excitation, which stresses are normally encountered in flight due to the angle of air inflow to a propeller unit. Thus, the ability of a blade to withstand flight stresses can be accurately predicted by simulating flight loadings in the laboratory. Accordingly, among my objects are the provision of a means for stressing propeller blades through vibratory excitation to determine the structural characteristics thereof.

The aforementioned and other objects are accomplished in the present invention by providing means for producing flatwise vibratory stresses in propeller blades by cyclically altering the pitch setting of the blades of a rotating propeller unit. Specifically, the apparatus includes a rotatable propeller hub having a plurality of sockets adapted to support propeller blades for movement about their longitudinal axes. Associated with each of the hub sockets is a pitch changing torque unit including positive stops for determining the range of cyclic pitch change movement. The torque units are actuated by hydraulic fluid medium under pressure, which is supplied thereto through a stationary "pineapple" having passages for the flow of fluid medium to and from the torque units under the control of a pitch cycling valve. The pitch cycling valve is actuated by a suitable motor and controls the flow of fluid to and from the hub torque units to cyclically alter the pitch position of the propeller blades under test. Fluid under pressure is produced by a pump having connection with a reservoir and with the supply port of the valve. The blades may be instrumented with strain gages to determine the magnitude of the stresses produced therein.

Further objects and advantages of the present invention will be apparent from the following description, reference being had to the accompanying drawings wherein a preferred embodiment of the present invention is clearly shown.

In the drawings:

Fig. 1 is a view in perspective of apparatus constructed according to the present invention.

Fig. 2 is a view partly in section and partly diagrammatic illustrating the principle of operation.

Referring more particularly to Fig. 1, the present invention is exemplified in conjunction to a propeller unit including a universal hub 10 having a plurality of radially extending sockets 11, which are adapted to receive a plurality of blades 12. The blades 12 are journaled for rotation about their longitudinal axes within the hub sockets 11 in a manner to be later described. The hub

2

10 is suitably supported and is adapted to be rotated by means of a motor 13. The hub 10 is further provided with a central through bore within which a stationary "pineapple" 14 is disposed. The stationary "pineapple" 14 is connected by tubing 15 and 16 to the outlet ports of a four-way cycling valve unit 17. The cycling valve unit 17 is operated by an electric motor 18 having connection therewith through a crank mechanism 19 and a connecting rod 20. Fluid medium under pressure is supplied to the supply port of the cycling valve unit 17 through tubing 21.

As previously mentioned, it is desirable to demonstrate the ability of propeller blades to withstand the stresses normally encountered in flight before the blades are installed on an aircraft. Existing test apparatus is inadequate in that flight loadings cannot be duplicated or even closely approximated. Furthermore, existing test apparatus produces extraneous stresses, which sometimes cause failure of the blades before the design flatwise vibratory bending stresses have been reached. The ability of a propeller blade to withstand flatwise vibratory bending stresses is indicative of the structural integrity of a propeller blade. Flatwise vibratory loads on propeller blades occur in flight when the air stream enters the propeller unit at an angle other than 90°. This phenomenon produces a flatwise bend cycle in each blade every revolution of the propeller unit due to sinusoidally varying aerodynamic loading. Accordingly, this phenomenon, which is known as a 1P bend, is an important criteria in the design of a propeller blade. The present invention provides a method and apparatus of simulating flight loadings of this character in the laboratory.

The flatwise bending is induced in propeller blades by cycling the pitch setting thereof in a predetermined relation to the rotational speed of the test unit. In other words, the flatwise bending is effected by exciting the blade torsionally. If the pitch is cycled once per revolution of the test unit hub, the stresses encountered by a 1P bend in flight may be closely approximated. The present invention provides means for obtaining this result, but has versatility in that the rotating blade may be excited at any desirable frequency with respect to the rotational speed thereof.

Referring more particularly to Fig. 2, the detail construction of the universal hub 10 and the principle of operation will be described in greater detail. The hub 10 is provided with a flange 22 to which the means for rotating the hub may be attached. The hub is provided with a central bore 23 within which a portion of the stationary "pineapple" 14 is mounted. Disposed within the socket 11 is an adapter 24 having a socket portion 25 adapted to receive and rotatably journal the root end of a propeller blade 12. The adapter 24 is merely provided to accommodate the various sizes of blades now produced. The blade 12 is supported within the adapter socket 25 by means of the conventional stacked bearings 26 and bearing retaining nut assemblies 27 and 28. As shown, the blade is spline connected by means of an indexing ring 29 to a central upstanding portion 30 of the adapter 24. The adapter 24 is likewise journaled for rotation by means of stack bearings 31 within the hub socket 11. Radial bearing means 32 are also provided between the adapter 24 and the hub 10.

Centrally disposed within the hub socket 11 is an upstanding integral portion of a hub 33 having a helically splined periphery 34. Coaxially disposed within the hub socket 11 is a piston 35 having an axially extending skirt 36 provided with helical splines 37 and 38 on its inner and outer peripheries, respectively. Helical splines 37 mate with helical splines 34 on the portion 33, and helical splines 38 mate with helical splines 39 formed on a ring 40, which is attached to the adapter 24 by means

of a dowel pin 41. The piston 35 forms part of a torque unit, the cylinder of which is formed by complementary portions of the hub 10 and the adapter 24. The torque unit is similar in construction and operation to the torque units disclosed in the Blanchard et al. Patent 2,307,101. One torque unit chamber 42 is connected by a transfer tube 43 formed integral with the hub 10 to an annular groove 44 circumscribing the central bore 23. The other torque unit chamber 45 is connected by means of a passage 46 to a second annular groove 47 likewise circumscribing the central bore 23. The stationary "pineapple" portion extending into the central bore 23 of the hub is provided with a pair of passages 48 and 49 having communication with ports 50 and 51, respectively. The ports 50 and 51 communicate, respectively, with annular grooves 44 and 47, which circumscribe the central bore 23 of the hub.

The passages 48 and 49 of the stationary "pineapple" 14 are shown as diagrammatically connected by means of lines 52 and 53 to the outlet ports 54 and 55 of the four-way cycling valve unit 17. The four-way cycling valve unit 17 includes a housing 56 having a supply port 57, the outlet ports 54 and 55 and a pair of drain ports 58 and 59. Disposed within the housing 56 is a plunger 60 having a pair of spaced lands 61 and 62 which cooperate with ports 55 and 54, respectively. A rod portion 63 of the plunger 60 extends through one end of the housing 56 and is connected by means of the connecting rod 20 to the crank mechanism 19, which is operatively connected with the motor 18. Fluid medium under pressure is developed by a pump 64 having connection with a reservoir 65.

As is readily apparent, rotation of the crank mechanism 19 by the motor 18 will effect a reciprocal movement of the plunger 60, thereby periodically connecting the lines 52 and 53 to the supply port 57 and to drain. In this manner fluid medium is periodically supplied to and drained from the torque unit chambers 42 and 45 whereupon the piston 35 will be reciprocated. Movement of the piston 35 is limited by engagement thereof with the portions of the hub 10 and the adapter 24, which define the torque unit cylinder. Reciprocal movement of the piston 35 is converted into rotary movement of the blade 12 through the medium of the helical splines 34, 37, 38 and 39. As the piston moves inwardly or outwardly with respect to the hub portion 33, a twisting or rotation occurs between splines 34 and 37. The movement of the piston skirt 36 also effects relative movement between spline teeth 38 and 39, thereby causing a rotating movement of the adapter 24, which rotation is the sum of that caused by spline teeth 34, 37, 38 and 39. This rotary movement is transmitted by means of the indexing ring 29 to the blade 12 in a manner similar to that described in the aforementioned Blanchard et al. patent. The cyclic pitch changing movement of the blades may, for example, be on the order of 6°.

In operation the test engineer will energize motor 13 to rotate the propeller hub 10 at any desired rotational speed. Thereafter, the motor 18 will be energized and the pump 64 will be set into operation whereupon the pitch setting of the propeller blade 12 will be cycled throughout a predetermined range of movement as determined by the positive stops within the torque unit. In this manner flatwise laboratory stresses may be produced in the propeller blades, the magnitude of which may be measured by any suitable means, not shown, such as strain gages. If the test engineer desires to ascertain the stresses induced in the blades by a 1P bend, he need only adjust the speed of the motor 18 so that the pitch of the blades 12 is cycled once per revolution of the hub 10. However, the apparatus is extremely versatile as the R. P. M. of the hub, the cyclic frequency and the cyclic pitch change angle may all be varied to suit the particular exigencies of the moment.

The production of vibratory blade stresses by the meth-

od of cyclic pitch changing is of considerable utility in that the vibratory aerodynamic loadings normally encountered in flight may be more nearly duplicated. In addition the possibility of creating extraneous stresses which often result in premature blade failure is substantially eliminated. Accordingly, the structural characteristics of a propeller blade and its ability to withstand stresses in flight may be accurately ascertained.

While the embodiment of the present invention as herein disclosed, constitutes a preferred form, it is to be understood that other forms might be adopted.

What is claimed is as follows:

1. Apparatus for inducing flatwise vibratory stresses in a propeller blade including, a hub having means for supporting a propeller blade for movement about its longitudinal axis, means disposed within said hub and operatively connected with said blade for moving the same about its longitudinal axis to alter the pitch setting thereof, means for rotating said hub, and means for cyclically altering the pitch setting of said propeller blade throughout a predetermined angle and in a predetermined relation to the rotational speed of said hub whereby flatwise bends are produced therein.

2. Apparatus for inducing flatwise vibratory stresses in propeller blades including, a hub having a plurality of sockets for supporting propeller blades for movement about their longitudinal axes, fluid pressure actuated means disposed within said hub and operatively connected with said blades for moving the same about their longitudinal axes to alter the pitch setting thereof, means for rotating said hub, and means for cyclically actuating the fluid pressure actuated means whereby flatwise bends are produced in said blades.

3. Apparatus for simulating flight stresses in propeller blades including, a hub having means for supporting a plurality of propeller blades for movement about their longitudinal axes, fluid pressure actuated means disposed within said hub and operatively connected with said blades for moving the same about their longitudinal axes to alter the pitch setting thereof, means for rotating said hub, and a fluid pressure system for cyclically actuating said fluid pressure actuated means whereby flight stresses are simulated by cycling the pitch setting of the blades during rotation of the hub.

4. The combination set forth in claim 3 wherein the fluid pressure system includes a pump and a valve in circuit connection between said pump and said fluid pressure actuated means, and means for actuating said valve independent of the rotation of said hub to produce cyclical changes in the pitch setting of said blades.

5. Apparatus for testing a propeller blade comprising in combination, a hub having means for supporting a propeller blade for movement about its longitudinal axis, a fluid pressure operated torque unit disposed within said hub and operatively connected to said blade for rotating the same about its longitudinal axis to alter the pitch position thereof, said torque unit comprising a cylinder having disposed therein a reciprocable piston capable of fluid pressure actuation in either direction, and means for converting reciprocative movements of the piston into rotary movement of said blade, means for rotating said hub, and means for cyclically actuating said torque unit so as to cyclically alter the pitch position of said blade throughout a predetermined angle and in a predetermined relation to the rotational speed of said hub whereby flatwise vibratory stresses are produced in said propeller blade.

6. Apparatus for testing a propeller blade comprising in combination, a hub having means for supporting a propeller blade for movement about its longitudinal axis, a fluid pressure operated torque unit disposed within said hub and operatively connected to said blade for rotating the same about its longitudinal axis to alter the pitch position thereof, said torque unit comprising a cylinder having disposed therein a reciprocable piston capable of

fluid pressure actuation in either direction, means to impart rotation to said blade upon reciprocation of said piston, and mechanical stop means limiting piston movement in both directions, means for rotating said hub and means for cyclically actuating said torque unit so as to cyclically alter the pitch position of said blade throughout a predetermined angle and in a predetermined relation to the rotational speed of said hub whereby flatwise bends are produced in said blade.

7. The combination set forth in claim 5 wherein the 10 last recited means comprises a fluid pressure system including, a source of fluid pressure and valve means interconnecting the source of fluid pressure and said torque unit, and wherein said apparatus includes means for

cyclically actuating the valve means to effect cyclic alteration of the pitch position of said propeller blade.
